UNITED STATES PATENT OFFICE.

JOSEPH ABNER, OF CHICAGO, ILLINOIS.

DESIGN FOR A LAMP-SHADE:

56,405.

Specification for Design. Patented Oct. 26, 1920.

Application filed March 22, 1920. Serial No. 367,877. Term of patent 3½ years.

To all whom it may concern:

Be it known that I, JOSEPH ABNER, a citizen of the United States, residing at Chicago, in county of Cook and State of Illinois, have invented a new, original, and ornamental Design for a Lamp-Shade, of which the following is a specification, reference being had to the accompanying drawing, forming part thereof which shows a front elevation of the lamp.

I claim:—

The ornamental design for a lamp shade as shown.

JOSEPH ABNER.
